UNITED STATES PATENT OFFICE

160,244

ELECTRIC FENCE GATE HANDLE

Elmer R. Blandin, Osage, Iowa

Application July 18, 1949, Serial No. 3,974

Term of patent 7 years

(Cl. D10—8)

To all whom it may concern:

Be it known that I, Elmer R. Blandin, a citizen of the United States, residing at Osage, in the county of Mitchell and State of Iowa, have invented a new, original, and ornamental Design for an Electric Fence Gate Handle, of which the following is a specification, reference being had to the accompanying drawing, forming part thereof.

Figure 1 is a side elevational view of an electric fence gate handle, embodying my new design.

Figure 2 is a top plan view thereof.

Figure 3 is an end elevational view of the same, and

Figure 4 is a vertical transverse sectional view

taken substantially upon the plane indicated by the section line 4—4 of Figure 1.

The dominant features of the design reside in the portion shown in full lines.

I claim:

The ornamental design for an electric fence gate handle, as shown and described.

ELMER R. BLANDIN.
